CLAIM

The ornamental design for a hair dryer with sensor, as shown and described.

DESCRIPTION

FIG. 1 is a perspective view showing our new design;

FIG. 2 is a front elevational view thereof;

FIG. 3 is a rear elevational view thereof;

FIG. 4 is a side elevational view thereof;

FIG. 5 is a top view thereof; and,

FIG. 6 is a bottom view thereof.

The broken line showing of the cord is for illustrative purposes only and forms no part of the claimed design.
